UNITED STATES PATENT OFFICE.

THOMAS B. ALLARDICE, OF MOUNTAIN LAKES, NEW JERSEY.

OIL BURNER.

Application filed November 27, 1926. Serial No. 151,121.

This invention relates to an oil burner, of the rotary type, and has for its object to provide, in a manner as hereinafter set forth, a burner of such class including means for greatly facilitating the vaporizing of the oil by the introduction of preheated atomized air, whereby the efficiency of the burner is materially increased at a substantial saving of fuel consumption.

Further objects of the invention are to provide, in an oil burner of the class referred to, new and novel means for the supply or introduction of air and oil and for the pre-heating of the air to greatly facilitate the vaporizing of the oil.

A further object of the invention is to provide, in an oil burner of the class referred to, new and novel means for the supply or introduction of air and oil and for the pre-heating of the air to facilitate the vaporizing of the oil and further to provide for the admixing with a combustible mixture, of oil and air, on the discharge of such mixture, of pre-heated air to facilitate combustion.

Further objects of the invention are to provide, in a manner as hereinafter set forth, an oil burner of the revolving type, which is simple in its construction and arrangement, formed of few parts, readily assembled and disassembled, strong, durable, compact, thoroughly efficient in its use and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of an oil burner, of the rotary type in accordance with this invention.

Figure 2 is a section on line 2—2 Figure 1. Figure 3 is a section on line 3—3 Figure 2. Figure 4 is a section on line 4—4 Figure 1. Figure 5 is a section on line 5—5 Figure 2.

Figure 6 is a vertical sectional view of a modified form of burner in accordance with this invention.

Figures 7 and 8 are vertical sectional views of other modified forms.

Referring to the drawings in detail 1 denotes an annular open top base, provided with supporting legs 2, detachably connected with the base 1 by set screws 3. The base 1 is formed with sockets 4 for the reception of the legs 2. The base 1 centrally of its bottom is formed with an opening 5 and with an upstanding tapered collar 6 having its inner face, at its lower end, forming a continuation of the wall of the opening 5. The opening 5 and collar 6 provide a clearance for the passage of a drive shaft 7, the latter being vertically disposed, and is operated from a motor 8, which is arranged below the base 1. It is to be understood that the base 1 can be supported in any suitable manner other than that as shown.

Both forms of the burner, as illustrated, have as a part thereof, an outer shell and an inner shell, referred to respectively and generally by the reference characters 9 and 10. The shell 9 is cylindrical in contour, that is to say in vertical section, and the shell 10 flaring in contour, that is to say in vertical section.

The shell 9 at its top is formed with a continuous inwardly extending annular flange 11 of arcuate contour. The shell 9 surrounds and is spaced from, a flaring sleeve 15 which at its upper end merges into the flange 11. The lower end of the sleeve 15 is provided with an inwardly extending upturned annular flange 16 which is curvi-

linear in cross section and forms a pre-heated air deflector. The inner side of the sleeve 15, below and in proximity to its point of joinder with the flange 11, at diametrically opposed points thereof, is formed with a ledge 17. The ledges 17 provide a pair of seats for a purpose to be presently referred to. The flange 11, at diametrically opposed points and at the top thereof, is formed with a vertically disposed, inverted U-shaped offset portion 18 having a squared edge 19.

At the point of joinder of the sleeve 15 with the flange 11, at diametrically opposed points, openings 20 are formed. The offset portions 18 form continuations of the openings 20. The offset portions 18 are cut away to provide seats 21. Mounted on the seats 21 is a closure strip 22 which is disposed diametrically with respect to the shell 9 and sleeve 15 and is arranged at the top of the shell 9.

Arranged within the sleeve 15, as well as

being spaced therefrom, and of less height than the height of said sleeve, is a vertically disposed, hollow bell-shaped member 23, which is open at its top and at its bottom, 5 and has its top formed with a pair of oppositely disposed channel-shaped suspension arms 24, 25, which are mounted on the seats formed by the ridges 17. The arms 24, 25, are closed by the strip 22, and the latter in 10 connection with the arms 25 provide an air heating chamber 26 having an inlet for each end thereof provided by an opening 20. The outlet of the chamber 26 is formed by the open top of the member 23, and is indicated 15 at 27. The diameter of the lower end of the member 23 is less than the diameter of the flange 16 and the lower end of the member 23 is spaced from said flange 16 and opposes the top edge of the latter. The member 23 20 forms a pre-heated air receiving chamber 28 which gradually increases in diameter from its inlet to its discharge end.

The shell 10 is interposed between the shell 9 and sleeve 15 and is arranged in 25 spaced relation relative to said shell 9 and sleeve 15. The flare of the shell 10 is less than the flare of the sleeve 15. The shell 10 is of greater height than the shell 9 and sleeve 15, but the top edge of the shell 10 30 is positioned below the upper end of the sleeve 15. The shell 10 depends a substantial distance below the lower end of the sleeve 15. The shell 10 is provided intermediate its ends with a right angularly disposed, 35 annular flange 12, which forms a shelf for an insulation body 13 and the latter is formed with an opening 14 through which extends the shell 9. The shelf 12 supports the shell 9. The shelf or flange 12 is provided with spaced inlet openings 29 positioned between the shell 9 and the shell 10, and said openings 29 are provided for supply 40 of air to an air receiving chamber 30 which is formed by the shell 10 in connection with the shell 9. The openings 20 form outlets 45 for the upper portion of the chamber 30. The shell 10 in connection with the sleeve 15, provides a pre-heating air chamber 31, which gradually increases in width from its upper 50 to its lower end and at its upper end communicates with the upper portion of the chamber 30. The lower end of the shell 10 is provided with an inwardly extending upturned flange 32, of curvilinear cross section, 55 and which is of greater width than the flange 16 and the diameter of the flange 32 at its free edge is less than the diameter of the flange 16 at its free edge. The flange 32 is spaced a substantial distance below the 60 flange 16 and provides a combined oil trap and deflector. The shell 10 at its bottom is formed with a depending annular rib 33 and a pocket 34, and extended into the pocket 34, and surrounded by the rib 33 is the upper 65 end of the base 1. The trap formed by the

flange 32 is arranged within the top of the base.

The bottom of the base 1 is formed with a discharge opening 35 for the overflow of oil from the flange 32 or from any other source 70 and adjacent said opening, the base 1 is furthermore formed with a vertically disposed semicircular flange 36 of materially less height than the height of the base and which forms a retarder. Connected to the 75 base 1, and surrounding and spaced from the flange 36 and of greater height than said flange, as well as extending over said flange 36 and secured to the side of the base 1, is a protector 37 provided with openings 80 for the passage of the oil overflow to the discharge opening 35, which communicates with an interiorly threaded nipple 39.

With reference to Figures 1 and 2, the drive shaft 7 has a reduced peripherally 85 threaded upper terminal portion 40 having a tapered free end 41. The reduced terminal portion 40 provides a shoulder 42. Mounted on the shoulder 42 and having said terminal portion 40 extending therethrough is a circular disk 43 which provides an oil baffle. Seated on the disk 43, as well as of greater diameter than said disk, and further having said terminal portion 40 extend through the bottom thereof, is a cup-shaped impeller 44 90 having its inner face formed with radially disposed vanes 45, which gradually increase in width from their inner ends towards the upper edge of the impeller 44. The vanes 45 have their inner or lower ends spaced a substantial distance from the axis of the impeller 44.

Threadably engaging with the terminal portion 40, is a hollow tapered oil distributing head 46, which is open at its upper end, 105 as at 47, and provided near its base with a circumferentially extending series of spaced jet openings which are radially disposed with respect to the axis of the head. The pointed end 41, of the terminal portion 40 110 extends into close proximity to the opening 47. The impeller 44 has the upper portion thereof opposite the edge of the flange 16, but is spaced therefrom to form an inlet for the passage of pre-heated air from the chamber 31 for admixing with a mixture of oil and air to be presently referred to. The admixing of the pre-heated air with the mixture of oil and air provides for satisfactory combustion during the operation of the 115 burner. The baffle 43, impeller 44, and head 46 bodily rotate through the action of the drive shaft 7. The top edge of the impeller 44 is positioned in alignment with the bottom edge of the bell-shaped member 23, but the impeller 44 is of greater diameter than the lower diameter of the member 23.

An oil supply line is indicated at 49 and extends from a suitable source of supply. The line 49 includes a vertically disposed 130

section 50, a horizontally disposed section 51 and a vertically disposed section 52. The upper end of the section 50 is connected to the outer end of section 51 by an elbow coupling 52. The inner end of the section 51 is connected to the upper end of the section 52 by an elbow coupling 54. The section 50 is arranged in the cold air receiving chamber 30. The section 51 extends through an opening 20 and lengthwise of the chamber 26 for a portion of the length of the latter. The section 52 extends down through the chamber 28 and into the open upper end of the distributor head 46. A retaining means, indicated at 55 associates with the section 51 for maintaining it stationary.

The oil enters through the line 49 and is discharged into the head 46, where due to centrifugal force it is broken and distributed to the impeller 44. Air enters through the inlets 29 and a portion thereof flows into chamber 26 where it is heated and the air also flows into the chamber 31 where it is heated. The heated air passes through chamber 26, into chamber 28, and then into the impeller, which acting upon the oil will facilitate the vaporizing thereof. The impeller 44, in view of the vanes 45, sets up a slight vacuum in chamber 28. The mixed air and oil is discharged from the impeller 44, at the edge thereof in connection with the edge of the member 23 and mixes with the pre-heated air from the chamber 31 which passes between the flange 16 and the impeller thereby facilitating combustion.

Referring to Figure 6, the oil supply line is indicated generally by the reference character 56 and is arranged in the same manner as the air supply line 49, with this exception that the section 57 of the line 56, which corresponds to the section 52 of the line 59, is of less height than said section 52. The drive shaft shown in Figure 2 is of less height than the drive shaft shown in Figure 6, and the drive shaft shown in Figure 6 extends up into the chamber 28 formed by the member 23. The drive shaft shown in Figure 6 has an upper peripherally threaded terminal 58 and said shaft intermediate its ends is formed with peripheral threads 59. Secured to the threaded terminal portion 58 of the drive shaft is a distributing head 60, which is hollow and also of tapered contour and provided at its upper end with an opening 61 into which extends the lower end of the pipe section 57 of the line 56. The distributing head 60 is formed with a circumferentially extending set of downwardly disposed jet openings 62 for the discharge of the oil therefrom. Mounted on the drive shaft is an impeller 62 having a centrally disposed horizontal portion 63 against which seats the head 60. The impeller 62 has its remaining portion extend downwardly and outwardly, as indicated at 64 and said por-

tion 64 has an upturned curved lower terminal 65. In other words the impeller 62 is convexed in cross section and has the major part thereof arranged in the chamber 28 and the upturned portion thereof extended towards the lower end of the member 23, but is spaced therefrom and also spaced from the upturned free edge of the flange 16. Secured to the threaded portion 59, of the drive shaft is a fan 66. The head 60, impeller 62 and fan 66 bodily revolve together on the operation of the drive shaft.

The distributing head, in both forms, provides for the oil to be carried in a thin film throughout the upper face of the impeller and which assists in the vaporizing of the oil and when the pre-heated air from the chamber 28 is supplied or conducted to the impeller, it admixes with the thin film of oil and facilitates the vaporizing thereof, and owing to the manner of setting up a second air pre-heating chamber, so that such pre-heated air can be discharged or taken up by the mixture of oil and air, unusually satisfactory combustion is provided for.

The modified form shown in Figure 7 is similar in construction to the form shown in Figures 1 and 2, with this exception that the bell shaped chamber 23, openings 20 and chamber 26 are dispensed with, and that the flaring sleeve 67 which corresponds to the sleeve 15 is formed with a single opening 68 of a diameter to snugly engage the section 51 of the oil supply line 49.

The modified form shown in Figure 8 is similar in construction to the form shown in Figure 6, with this exception that the bell shaped chamber 23, openings 20 and chamber 26 are dispensed with, and that the flaring sleeve 69, which corresponds to the sleeve 15 is formed with a single opening 70, of a diameter to snugly engage the section 51 of the oil supply line 49.

In the form shown in Figures 7 and 8, the air pre-heating bell and assembly, as shown in connection with Figure 1, are dispensed with, and the sleeve 67 or 69, provides an uninterrupted mixing chamber.

Although, as shown, the flare of the shell 10 is less than the flare of the sleeve 15, or 67 or 69, it is to be understood that the shell 10 can be perpendicular if desired.

The construction described, provides a very satisfactory oil burner of the rotary type and operates in a manner to obtain a saving in fuel consumption, and although the preferred embodiments of the several structural elements of the device are as illustrated and described, yet it is to be understood that changes in the details of construction of such elements can be had, which will fall within the scope of the invention as claimed.

What I claim is:

1. An oil burner comprising an air receiv-

ing chamber, a pair of air pre-heating chambers communicating with said air receiving chamber, one of said air pre-heating chambers arranged within the other and of bell-shaped contour, a rotary impeller for vaporizing oil arranged below and in close proximity to the lower end of said bell-shaped chamber, a distributor head rotating with said impeller and provided with ports for distributing oil in jet like form upon the impeller, said impeller receiving pre-heated air from said bell-shaped chamber to facilitate the vaporizing of the oil, and means to provide for the passage of pre-heated air from the other of said air heating chambers to admix with the oil vapor and air on the discharge of the same from the impeller for combustion.

2. An oil burner constructed in accordance with claim 1, an oil supply line extending through said air pre-heating chambers and opening into the upper end of said distributor head.

3. An oil burner constructed in accordance with claim 1, means for carrying off the overflow of oil and arranged below the said chambers and impeller.

4. An oil burner comprising an air receiving chamber, a pair of air pre-heating chambers, one surrounded by the other, the inner of said chambers being of bell-shaped contour, said air receiving chamber surrounding the outer air pre-heating chamber, a revoluble impeller for vaporizing oil, said impeller arranged below and in proximity to the bottom of said bell-shaped chamber and provided with ports for distributing oil in jet like form to said impeller, a stationary oil supply line extending through said air pre-heating chambers and discharging into the upper end of said distributor, and means to provide for the passage of pre-heated air from the outer of said air pre-heating chambers to admix with the oil vapor and air discharge from said impeller for combustion.

5. An oil burner comprising a horizontally disposed cup shaped rotary impeller for vaporizing oil and provided with radial vanes on its upper face, said means having the inner ends thereof spaced from the axis of the impeller and gradually increasing in width from their inner towards their outer ends, means carried by the impeller, rotating therewith, and disposed axially thereof for distributing oil in jets upon the upper face of the impeller, and means for supplying preheated air to the vapor when discharged from the impeller for combustion.

6. An oil burner comprising a horizontally disposed rotary impeller for vaporizing oil and provided with radial vanes on its upper face, said means extending from a point remote from the axis of the impeller to the outer edge thereof and gradually increasing in width from their inner towards

their outer ends, means carried by the impeller axially thereof, rotating therewith and providing for discharging oil in jets upon the upper face of the impeller, means for preheating air, means for conducting preheated air to the upper face of the impeller, and means providing for the passage of preheated air to admix with the vaporized oil when discharged from the impeller for combustion.

7. An oil burner comprising an inner and outer chamber for heating air and communicating with each other at the top thereof, an air receiving chamber opening into said outer chamber at the top thereof, a horizontally disposed rotary impeller for vaporizing oil disposed at the lower end of the inner chamber and taking heated air therefrom, means carried by the impeller axially thereof, rotating therewith and distributing oil in jets thereon, and means to provide for conducting heated air from the outer of said chambers to admix with the oil vapor and air when discharged from the impeller.

8. An oil burner constructed in accordance with claim 7, having an oil supply line extending through said air receiving and inner air heating chambers and opening into the upper portion of said distributing means for discharging oil therein.

9. An oil burner comprising a horizontally disposed rotary impeller for vaporizing oil, an air heating means, a mixing chamber surrounded by said heating means, said impeller arranged at the lower portion of said mixing chamber, an oil distributor head secured to said impeller, bodily rotated therewith and discharging oil in jet like form upon the impeller, said distributor head closed at its bottom, an oil feed line extending through said mixing chamber into the upper end of the distributor head and discharging oil therein, and means to provide for the passage of heated air from said air heating means to admix with the vaporized oil when discharged from said impeller.

10. An oil burner comprising an outer air entrance chamber, a plurality of inner air heating chambers arranged one within the other, and surrounded by said air entrance chamber, the outer chamber for heating air depending below the air entrance and inner air heating chambers, the walls of the said several chambers forming baffles arranged relatively to each other to provide for the air following a distinct direction.

11. An oil burner comprising a horizontally disposed rotary impeller for vaporizing oil and having its upper face formed with radially disposed vanes, means for distributing oil in jet like form throughout upon the impeller, an outer air entrance chamber, inner air preheating chambers arranged one within the other, surrounded by and communicating at their tops with the top of the

air entrance chamber, the walls of said chambers forming baffles arranged relatively to each other to provide for the air following a distinct direction towards said impeller 5 to admix with the vaporized oil.

12. An oil burner comprising a horizontally disposed rotary impeller for vaporizing oil, means for supplying oil to said impeller, an air entrance chamber, an air preheating 10 chamber surrounded by said entrance chamber and opening at its top into the top of the latter, a mixing chamber surrounded by said preheating chamber and having said impeller arranged therein at the lower portion thereof, 15 said preheating chamber depending below said entrance and mixing chambers, said mixing chamber having its lower end open, and the wall of the mixing chamber having its lower end provided with means 20 positioned above the bottom of said preheating chamber for directing preheated air from the latter into the mixing chamber at the edge of the impeller.

13. An oil burner comprising an air receiving chamber, an inner and an outer air preheating chamber surrounding each other and communicating with said air receiving chamber, said outer air preheating chamber surrounded by said air receiving chamber, 25 said inner chamber open at its lower end, a rotary impeller positioned in close proximity to the lower end of said inner chamber, a distributor head rotating with said impeller 30

and provided with ports for distributing oil in jet like form upon the impeller, said impeller receiving preheated air from said inner chamber to facilitate the vaporizing of the oil, and means to provide for the passage of preheated air from the other of said preheating chambers to admix with the oil and 35 air on the discharge of the same from the impeller for combustion.

14. An oil burner comprising an air receiving chamber, an outer and an inner air preheating chamber communicating with 40 said air receiving chamber, a mixing chamber, said air receiving chamber surrounding the outer air preheating chamber, said mixing chamber surrounding the inner air preheating chamber, a rotary impeller for vaporizing oil arranged below said inner air preheating chamber and within the lower 45 end of the mixing chamber, a distributor head rotating with said impeller and provided with ports for distributing oil in jet like 50 form upon the impeller, said impeller receiving air from said inner chamber to facilitate the vaporizing of the oil, and means to provide for the passage of preheated air from the outer air receiving chamber to admix 55 with the oil and vapor on the discharge of the same from the impeller into the mixing chamber for combustion.

In testimony whereof, I affix my signature hereto.

THOMAS B. ALLARDICE.
